United States Patent Office.

ISAAC T. MONTROSS, OF PEEKSKILL, NEW YORK,

Design No. 4,236, dated July 19, 1870.

DESIGN FOR A STOVE.

The Schedule referred to in these Letters Patent and making part of the same.

To all whom it may concern:

Be it known that I, ISAAC T. MONTROSS, of Peekskill, in the county of Westchester and State of New York, have invented or produced a new and original Design for a Heating-Stove; and the following is declared to be a correct description thereof.

The accompanying photograph represents this stove and the design of the ornamentation and the configuration.

The base *a* is circular, and above this is the ash-pit *b*, having a compound curved or ogee-shape sectionally, with vertical leaflet ornaments.

The flaring open-work at *c* surrounds the fire-pot, and above this is the ornamental ring *d*.

The windows *e* are of a Gothic arch, with ornamental side columns and sill, and the combustion-chamber, in which said windows are placed, is of a dome shape.

The ornamental ring *f* forms a base to the cylinder *g*, the surface of which cylinder is ornamented with scrolls and vines around a circular frame, within which are rays or grooves diverging from a central ornament.

The top *l* of the stove is made generally in the form of a flattened cone, with ornamental rings or bands with concave and convex lines intervening, as shown, and the stove may be surmounted with an urn.

I claim as my invention—

The design of the shape and ornamentation of the parts *b c e f g*, as described and represented.

Signed by me this 13th day of June, A. D. 1870.

ISAAC T. MONTROSS.
